HANDBAG CLOSURE CLASP

Etienne Aigner, 217 Haven Ave., New York, N.Y.

Filed Oct. 16, 1963, Ser. No. 76,998

Term of patent 14 years

(Cl. D87—2)

FIG. 1

FIG. 3

FIG. 5

FIG. 2

FIG. 4

FIG. 1 is a top plan view of handbag closure clasp showing my new design;

FIG. 2 is a front elevational view thereof;

FIG. 3 is a side elevational view thereof;

FIG. 4 is a rear elevational view thereof; and

FIG. 5 is a sectional view taken on the line 5—5 of FIG. 1.

I claim:

The ornamental design for a handbag closure clasp, substantially as shown.
